(57) **CLAIM**

The ornamental design for a communications device as shown and described.

DESCRIPTION

FIG. 1 is a perspective view of a first embodiment of a communications device showing my new design; and FIG. 2 is a front elevational view thereof.

FIG. 3 is a perspective view of a second embodiment of a communications device showing my new design; and FIG. 4 is a front elevational view thereof.

FIG. 5 is a perspective view of a third embodiment of a communications device showing my new design; and, FIG. 6 is a front elevational view thereof.

The broken lines depict portions of the communication device that form no part of the claimed design.

An unshaded surface shown between a first outer solid line and a first inner solid line is included in the claim, and forms part of the claimed design. A surface with oblique surface shading between the first inner solid line and a second inner solid line is a transparent surface, and forms part of the claimed design.
